UNITED STATES PATENT OFFICE.

CLAUDE L. POST, OF CHICAGO, ILLINOIS.

INKING MECHANISM.

Application filed June 4, 1921. Serial No. 474,912.

To all whom it may concern:

Be it known that I, CLAUDE L. POST, a citizen of the United States, residing at Chicago, in the county of Cook and State 5 of Illinois, have invented certain new and useful Improvements in Inking Mechanisms, of which the following is a description.

My invention relates to inking mechanisms, and more particularly to an inking 10 roll having an ink-receiving reservoir therein which may be conveniently filled, and being provided with means whereby the ink in said reservoir may be fed to the inking surface of the inking roll intermittently.

Another object of my invention is to provide means for reciprocating the inking roll while it is being rotated so that the ink 15 is more evenly distributed on the cooperating inking rolls or distributing rolls over 20 their entire surfaces.

Another object of my invention is to provide a device of the character described which may be easily assembled or disassembled for inspection or the like, and which 25 is extremely simple, durable, compact, efficient and satisfactory for use wherever found applicable.

Many other objects and advantages of the construction herein shown and described will 30 be obvious to those skilled in the art from the disclosure herein given.

To this end my invention consists in the novel construction, arrangement and combination of parts herein shown and described, 35 and more particularly pointed out in the claims.

In the drawings, wherein like reference characters indicate like or corresponding parts,

Figure 1 is an end elevation of a portion 40 of a printing frame with my device in place;

Fig. 2 is a front elevation of the same;

Fig. 3 is a section taken substantially on the line 3-3 of Fig. 1;

Fig. 4 is a sectional view taken substantially on the line 4-4 of Fig. 1;

Fig. 5 is a sectional view taken substantially on the line 5-5 of Fig. 4;

Fig. 6 is a sectional view taken substantially on the line 6-6 of Fig. 2;

Fig. 7 is a top view of the inking roll held in position in the frame;

Fig. 8 is an enlarged sectional view taken on the line 8-8 of Fig. 7;

Fig. 9 is an enlarged sectional view taken 55 on the line 9-9 of Fig. 7;

Fig. 10 is a sectional view taken substantially on line 10-10 of Fig. 8; and

Fig. 11 is a fragmentary plan view of the inking roll shown in Fig. 8. 60

Referring to the drawings, wherein I have illustrated the preferred embodiment of my invention, 1 indicates the side frames of a printing mechanism of any suitable or desired construction, said frame having upwardly extending pairs of arms 2-2 at its opposite sides, and there being a slot 3 between each of said pair of arms. Rolls 4, 5, 6, and 7 are suitably held in place or carried by said frame, the rolls 4 and 5 being 65 adjustably journaled therein in journal boxes 8, as shown in Figs. 1 and 2. The rolls 4 and 5 are suitably geared together or driven by any suitable means, not shown.

The shaft 9 of the roll 6 is annularly 75 slotted at 10 so as to receive the yoked end 11-11 of a reciprocating arm 12, said arm being pivoted at its end 13 and adapted to be oscillated on said pivot through suitable gearing. The gearing for oscillating the arm 80 12 comprises a worm gear 14 at the end of the drive shaft 15 of the roll 5, said worm meshing with a gear wheel 16, carried by an arm 17 secured to the frame in any suitable manner. A pin 18 projects from the face 85 of the gear wheel 16, and is adapted to slide in a longitudinal slot 19 provided in the arm 12, said pin 18 being eccentric to the pivotal axis of the gear wheel 16. It is obvious that as the shaft 15 rotates, the worm 90 14 will rotate the gear wheel 16 and the eccentrically mounted pin 18 will slide in the slot 19 to oscillate the arm 12 on the pivot 12, this movement being transmitted to reciprocate the roll 6. 95

The inking roll 7 is in frictional contact with the roll 6, as shown in Figs. 1 and 2, the shaft 20 supporting said roll at its ends. A bearing sleeve 21 surrounds the shaft 20, said bearing sleeve being cut away or recessed 100 between its ends, as at 22, on opposite sides so as to nonrotatably fit between the opposed pair of frame arms 2, as shown in the drawings. In order to prevent longitudinal or axial movement of the sleeve relatively to the frame, a collar 23 is positioned about the sleeve and adjustably secured thereto by a set screw 24, or any other suitable or

equivalent means for the purpose, the collar 23 being recessed on opposite sides, as at 25, and providing shoulders 26 overlying the opposite sides of the frame arms 2, thus preventing relative lateral movement therebetween, but permitting the sleeve, with its attached collar, to be slid into place downwardly between the spaced arms 2, as shown in Fig. 1. The collar 23 is of a lesser length 10 than the length between the shoulders or ends of the recesses 22 so that the sleeve may be adjusted relative thereto.

The inking roll 7 has an ink well or ink-receiving chamber 27 therein, said chamber 15 being formed by slotting the roll longitudinally thereof, said slot opening on the periphery of the roll. Within the chamber 27 is revolvably mounted a roller 28, supported by a shaft 29 at its ends, the periphery of the 20 roller being substantially flush with the peripheral surface of the roll 7, as shown in Fig. 9. At one end of the shaft 29 is mounted a gear or ratchet wheel 30, said gear being adapted to be intermittently engaged by a 25 preferably resilient or yieldable tooth member 31 carried by the sleeve 21. As the roll 7 is in frictional contact with the roll 6, it is driven and reciprocated thereby, and the teeth of the gear 30 which is eccentrically 30 mounted relative to the rotational axis of the roll 7 will be intermittently engaged by the laterally offset or projecting tooth end 32 of the resilient member 31, as shown in Figs. 2 and 6, whereupon the roller 28 will 35 be partially rotated relative to the rotation of the roll 7 so as to carry the ink to the periphery of the roll 7, where it may be distributed to the roll 6 and to the type roll, as desired.

40 The ink reservoir may be closed by any suitable means, and removably held in place. In the embodiment shown, the cover 33, having downturned or laterally offset ends 34, is pivotally mounted on the roll 7 by screws 45 35 through said ends, or any other equivalent means for the purpose, said cover being arcuate or curved in cross section to conform to the peripheral surface of the roll 7, and overlying one edge of the slotted chamber 50 27. The screws may be tightened to hold the cover firmly in place, or any other suitable or preferred latching means, such as a spring-pressed detent, may be used.

55 Whenever it is desired to fill the chamber or to open it for inspection, or for any other desired purpose, the cover is drawn back, as shown by the dotted lines in Fig. 9, whereupon easy access is had to the chamber 27 and to the parts therein.

60 Having thus described my invention, it is obvious that various immaterial modifications may be made in the same without departing from the spirit of my invention; hence I do not wish to be understood as limiting myself to the exact form, arrangement,

construction and combination of parts herein shown and described, or uses mentioned.

What I claim as new and desire to secure by Letters Patent is:

1. An inking roll having a longitudinal 70 ink-receiving slot opening on the periphery thereof, a roller revolvably mounted in said slot substantially flush with the periphery of the inking roll, and a circumferentially extending cover carried by said roll and 75 having its exterior curvature the same as that of said roll to form a portion of the peripheral inking surface thereof and circumferentially overlying the peripheral edge of said slot. 80

2. An inking roll having a longitudinal ink-receiving slot therein opening on to the periphery thereof, a revoluble roller mounted in said slot so as to be substantially flush with the inking periphery of said roll, 85 means for rotating said roller relative to the rotation of said roll, and a curved cover pivotally carried by said roll at the ends thereof adapted to form a portion of the peripheral inking surface of the roll, said 90 cover normally overlying the peripheral edge of said slot.

3. An inking roll having a longitudinal ink-receiving slot therein opening onto the periphery thereof, a revoluble roller mounted 95 in said slot so as to be substantially flush with the inking periphery of said roll, means for rotating said roller relative to the rotation of said roll, and a curved cover adapted to circumferentially overlie the peripheral edge of said slot, said cover being curved and having laterally offset ends, and means for pivotally securing said cover to said roll at said offset ends. 100

4. In combination with a printing frame, 105 an inking roll slidably carried by said frame and having an ink-receiving slot in its peripheral face, a roller revolvably mounted in said slot and having its rotational axis parallel to and eccentric relative to the rotational axis of the roll, a gear carried by said roller, a toothed member carried by said frame and intermittently engageable with said gear, said tooth being axially spaced from said gear, and means 110 for reciprocating said roll to operatively engage said gear and tooth. 115

5. In combination with a printing frame, 120 an inking roll having an ink-receiving slot in its peripheral face, a roller revolvably mounted in said slot and having its axis eccentric to the rotational axis of the roll, means for reciprocating and rotating said roll, and means for intermittently operating said roller, said means comprising a gear fixed on said roller, and a yieldable tooth stationary on said frame and axially spaced from said gear so as to be intermittently engageable therewith during one part 125 of said reciprocatory movement. 130

6. In combination with a printing frame, an inking roll having an ink-receiving slot in its peripheral face, a roller revolvably mounted in said slot and offset from the 5 rotational axis of the roll, friction means for rotating and reciprocating said roll, and means for intermittently operating said roller, said means comprising a gear fixedly carried by said roller, a bearing sleeve slidably carrying the shaft of said roll, and a tooth projecting from said bearing sleeve and engageable with said gear at one part 10 of said reciprocatory movement.
7. In combination with a printing frame, 15 an inking roll having an ink-receiving slot in its peripheral face, a roller revolvably mounted in said slot and offset from the rotational axis of the roll, friction means for rotating and reciprocating said roll, and means for intermittently operating said 20 roller, said means comprising a gear carried by said roller, a bearing sleeve slidably carrying the shaft of said roll, said sleeve being adjustable axially of said shaft, means 25 for normally preventing axial movement of said sleeve, and a resilient tooth projecting

from said sleeve and engageable with said gear at a portion of said reciprocatory movement.

8. In a device of the kind described and 30 in combination, a printing frame, an inking roll rotatably and slidably mounted in said frame, a second roll parallel to said inking roll and rotatably and slidably mounted in said frame, means for rotating and reciprocating 35 said last mentioned roll, said rolls being in frictional contact, whereby said rotational and reciprocatory movement is transmitted from the second to the first roll, a sleeve at the ends of said inking roll for 40 supporting it in said frame, said sleeve being removably arranged in said frame, and means for adjusting said sleeve axially of said roll.

In testimony whereof, I have hereunto 45 signed my name in the presence of two subscribing witnesses.
